UNITED STATES PATENT OFFICE.

CORREL WELTON JOHNSON, OF NEW YORK, N. Y.

SOUND CLARIFIER.

Application filed March 20, 1920, Serial No. 367,412. Renewed July 1, 1922. Serial No. 572,306.

To all whom it may concern:

Be it known that I, CORREL WELTON JOHNSON, a citizen of the United States, and a resident of the city of New York, borough of Manhattan, in the county and State of New York, have invented a new and Improved Sound Clarifier, of which the following is a full, clear, and exact description.

The invention relates to sound clarifiers for sound producing or reproducing instruments such as shown and described in the Letters Patent of the United States, No. 1,240,050, granted to me on September 11, 1917.

The object of the present invention is to provide a new and improved sound clarifier more especially designed for use in the amplifying chamber of a phonograph and arranged to eliminate dead air spaces and to insure a circulation of live air throughout the length of the amplifying chamber to induce clarification of the sounds and to avoid muffling of the same.

Another object is to prevent the formation of counter currents, eddies and other interfering motions within the amplifying chamber, thus insuring the production of a strengthened, amplified, tensified and clarified tone and eliminating flat or inharmonious sounds.

With these and other objects in view, the invention consists of certain novel features of construction as hereinafter shown and described and then specifically pointed out in the claims.

A practical embodiment of the invention is represented in the accompanying drawings forming a part of this specification, in which similar characters of reference indicate corresponding parts in all the views.

Figure 1 is a sectional side elevation of the improved sound clarifier as applied to a phonograph of usual construction;

Figure 2 is an enlarged sectional side elevation of the improved sound clarifier on the line 2—2 of Figure 3;

Figure 3 is a sectional front view of the same on the line 3—3 of Figure 2;

Figure 4 is a rear end view of the sound clarifier looking in the direction of the arrows on the line 4—4 of Figure 2;

Figure 5 is an enlarged sectional side elevation of a modified form of the sound clarifier;

Figure 6 is a sectional front elevation of the same on the line 6—6 of Figure 5; and

Figure 7 is a rear end elevation of the same.

The improved sound clarifier is shown applied to a phonograph of general construction and having a casing 10 provided with a hinged cover 11 and having a top 12 supporting a drive mechanism 13 for rotating the platform 14 carrying the record 15 engaged by the stylus 16 held on the sound box 17 mounted on the tone arm 18 adapted to swing on the top 12. The sound arm 18 is connected with a sound conveyor 20 attached to the under side of the top 12 and this sound conveyor 20 is gradually enlarged toward its outlet 21 which extends horizontally and is connected with the rear end or throat 22 of an amplifying chamber, box or horn 23 mounted in the casing 10 and having its front end 24 opening into the atmosphere surrounding the phonograph.

Into the outlet 21 of the sound conveyor 20 fits a throat member 30 provided with a comparatively large central opening 31 opening into the throat 22 of the amplifying chamber 23. The throat member 30 is provided adjacent the corners with small openings 32 each having a flaring mouth 33 opening into the discharge end 21 of the sound conveyor 20. The rear edges of each mouth 33 are knife-like and hence form no obstruction to the passage of a portion of the sound waves coming through the sound conveyor 20, it being understood that the major portion of the said sound waves passes through the central opening 31 and the remaining portions of the sound waves pass through the apertures 32.

Within the amplifying chamber 23 is arranged a hollow deflecting means, preferably in the form of one, two or more hollow deflectors 40: for instance, two such deflectors as shown in Figures 1, 2 and 3, or a single one as illustrated in Figures 5, 6 and 7. Each of the deflectors 40 has a pointed inner end 41 in register with the central opening 31 of the throat member 30, and each deflector 40 has one or more tubular connections with the corresponding aperture 32. Each tubular connection comprises a short tube 50 screwed or otherwise secured into the wall of the corresponding aperture 32 and this tube 50 projects horizontally from the front of the throat 30 and telescopes with the rear end of a tube 51 opening into the corresponding deflector 40 adjacent the corresponding point 41. In

order to direct the sound waves coming through the tubular connections from the apertures 32 in a forward direction within the corresponding deflectors 40 the rear ends 5 thereof are provided with plugs 42 provided with inclined faces to direct the sound waves forwardly within the hollow deflectors 40. It will be noticed that by the arrangement described the tubular connections connecting 10 the throat 30 with the deflecting means form a support for the deflecting means to hold the latter within the amplifying chamber 23 and with the walls of the deflecting means practically parallel with the walls of the 15 amplifying chamber 23 to provide a symmetrical, uniform passageway between the walls of the deflecting means and the walls of the amplifying chamber. In case two or more deflectors 40 are used then the same 20 are connected with each other near their rear ends by a suitable bridge or bracket 43, as plainly shown in Figures 1, 2 and 3.

It is understood that the amplifying chamber 23 gradually increases from the 25 throat to the mouth, and the deflectors 40 are correspondingly constructed, but their open forward ends preferably terminate a distance from the mouth 24 of the amplifying chamber 23. By the arrangement described 30 dead air spaces in the amplifying chamber and the deflectors 40 are eliminated and hence the sound waves are not liable to be muffled as a free circulation of live air is had throughout the amplifying chamber 35 23 and the deflectors 40. It will further be noticed that the major portion of the sound waves, coming through the sound conveyor 20 as an elastic body, pass through the opening 30 and come in contact with the walls of 40 the deflectors or deflector 40 and are deflected by the same against the walls of the amplifying chamber 23. The remaining or minor portion of the sound waves coming through the sound conveyor 20 pass into the 45 deflector or deflectors 40 to produce resonated sound waves or augmented harmonic tones which coalesce with the clarified sound waves passing through the amplifier 23. It will be noticed that the enclosed air molecules 50 are divided and serve to prevent interference of counter currents or eddies, due to vibration of the sound waves resulting from oscillation of the air molecules transmitting sound, whereby the sound is 55 strengthened, amplified and tensified and the tone clarified so that all flatness of sounds out of harmony with the sounds sought to be reproduced are eliminated.

It is understood that a hollow deflector 60 of shell formation is utilized as an auxiliary resonator of smaller compass than the amplifying chamber to preserve the delicate harmonics heretofore lost with the reverberations at the restricted end of the 65 amplifying chamber, and as the smaller de-

flector 40 gives greater response to tones of high register and is used in combination with a resonator of larger compass which has a greater response to tones of lower and middle register it insures a further clarification of the sounds emitted at the mouth 24 and adds to the tone quality.

Having thus described my invention, I claim as new and desire to secure by Letters Patent:—

1. A sound clarifier for a sound producing instrument having an amplifying chamber and a sound conveyor connected thereto, said clarifier comprising a hollow resonating deflector positioned within the amplifying chamber and having a closed, pointed inner end and having an open outer end, the said deflector coacting with the walls of the amplifier for deflecting the major portion of the sound waves delivered 80 by the said sound conveyor against the walls of the amplifying chamber, and a connection connecting the said sound conveyor with the interior of the said deflector adjacent the closed pointed end to conduct the 85 remaining portion of the sound waves coming from the sound conveyor through the said deflector.

2. A sound clarifier for a sound producing instrument having an amplifying chamber and a sound conveyor connected thereto, said clarifier comprising a hollow resonating deflector positioned within the amplifying chamber and having a closed pointed inner end and having an open outer 95 end, the said deflector coacting with the walls of the amplifier for deflecting the major portion of the sound waves delivered by the said sound conveyor against the walls of the amplifying chamber, a throat member fitted into the outlet of the sound conveyor and having a central opening in register with the said pointed inner end of the resonating deflector, the said throat member having an auxiliary opening, and a connecting tube connecting the said auxiliary opening with the interior of the said deflector adjacent the closed pointed inner end.

3. A sound clarifier for a sound producing instrument having an amplifying chamber and a sound conveyor connected thereto, said clarifier comprising a hollow resonating deflector positioned within the amplifying chamber and having a closed pointed inner end and having an open outer 100 end, the said deflector coacting with the walls of the amplifier for deflecting the major portion of the sound waves delivered by the said sound conveyor against the walls of the amplifying chamber, a throat member fitted into the outlet of the sound conveyor and having a central opening in register with the said pointed inner end of the resonating deflector, the said throat member having an auxiliary opening, and a connecting tube connecting the said auxiliary opening with the interior of the said deflector adjacent the closed pointed inner end.

necting tube connecting the said auxiliary opening with the interior of the said deflector adjacent the closed pointed inner end, the said connecting tube forming a support 5 for the deflector and being made in telescoping sections.

4. A sound clarifier for a sound producing instrument having an amplifying chamber and a sound conveyor connected thereto, to, said clarifier comprising a hollow resonating deflector positioned within the amplifying chamber and having a closed pointed inner end and having an open outer end, the said deflector coacting with the 10 walls of the amplifier for deflecting the major portion of the sound waves delivered by the said sound conveyor against the walls of the amplifying chamber, a throat member fitted into the outlet of the sound conveyor and having a central opening in register with the said pointed inner end of the resonating deflector, the said throat member having at least one comparatively small opening provided with a flaring mouth opening into the sound conveyor, and a tube engaging the said small opening and leading into the said resonating deflector adjacent the pointed end thereof.

5. A sound clarifier for a sound producing instrument having an amplifying chamber and a sound conveyor connected thereto, said clarifier comprising a hollow resonating deflector positioned within the amplifying chamber and having a closed pointed inner end and having an open outer end, the said deflector coacting with the walls of the amplifier for deflecting the major portion of the sound waves delivered by the said sound conveyor against the walls of the amplifying chamber, a throat member fitted into the outlet of the sound conveyor and having a central opening in register with the said pointed inner end of the resonating deflector, the said throat member having at least one comparatively small opening provided with a flaring mouth opening into the sound conveyor, and a tube engaging the said small opening and leading into the said resonating deflector adjacent the pointed end thereof, the said tube forming a support for the deflector to hold the same in spaced relation to the walls of the amplifying chamber.

6. The combination with an amplifying chamber of rectangular cross section and tapered toward its inlet end, of a sound conveyor and a clarifier embodying a substan-

tially pyramidal shell supported in said chamber to deflect the sound waves uniformly therearound, said shell being entirely closed at its apex and being provided with a tapered end terminating adjacent the mouth of the sound conveyor, the open base of the shell terminating within the chamber a short distance from the mouth of the conveyor. 60

7. The combination with a horn of a reproducing instrument tapering in one direction and a sound conveyor connected thereto, of a deflector positioned in the horn and having an inlet tapered end and having the 70 base or outlet end left entirely open.

8. An improved sound clarifier of a sound-producing instrument, which comprises a deflector of shell formation terminating in a point at its apex and with its base open, 75 an amplifying chamber within which said deflector is disposed and supported by tubular members, and a sound conveyor attached to one end of the amplifying chamber, said tubular members affixed within the conveyor 80 for the purpose of creating independent passage for sound waves into said deflector.

9. The combination with an amplifying chamber of a sound producing instrument and a sound conveyor connected thereto, of 85 an improved sound clarifier in the form of a shell deflector positioned within the chamber, and supported independently of the latter to receive sound waves through orifices cut at spaced points at tubular support connections.

10. A shell deflector positioned in a sound box or tone chamber, having telescopic tubular supports for the purpose of adjusting 90 said shell deflector in proper position.

11. A system of improved sound clarifiers of multiple resonating deflectors, each of said deflectors having orifices cut in one of its walls adjacent its apex, the inner wall of said apex converging from said orifices to 95 its opposite wall for the purpose of converging the sound waves from the multiple orifices into one unit.

12. The combination with a horn of a reproducing instrument tapering in one direction and a sound conveyor connected thereto, of a deflector of shell formation having a closed inner end and positioned within the 105 said horn, and tubular supports for the said deflector fixed within the sound conveyor 110 and forming an independent passage for the sound waves into the deflector.

CORREL WELTON JOHNSON.
